VIRGINIA.

INTERNAL-COMBUSTION ENGINE

Application filed July 15, 1919, Serial No. 310,978. Renewed April 1, 1925.

My invention relates to internal combustion engines, more especially of the oil burning injection type, independent of whether it is a two or four stroke cycle.

5 The object of the invention is to provide an improved engine in which supercompressed air is injected into the combustion chamber during a part of the stroke for the purpose of creating turbulence and effecting 10 a thorough intermingling of the air and fuel and thus assisting the fuel vaporization and combustion.

The invention consists of structural features and relative arrangement of parts 15 which will be hereinafter more fully described and particularly pointed out in the appended claims.

In the drawing, in which similar reference characters indicate the same parts in the several figures,

20 Figure 1 is a longitudinal section, with parts in elevation, of the fuel end of the engine cylinder showing the preferred form of my invention, and in which the left half 25 of the figure shows the relation of the elements when the piston is beginning the super-compression of the air, while the right half shows the position of the parts when the piston is at the end of its compression stroke.

30 Figure 2 is a bottom view of the distributor plate forming one of the important elements of my invention.

Referring to the drawings, 10 represents the cylinder which is provided with the usual 35 combustion chamber 10', head 11 and liner 12. 13 is the piston within the cylinder which is provided at its upper and outer edge with an annular recess 14 in which is seated and secured by means of screws or 40 other fastening means 15, a displacement ring 16 for the purposes to be hereinafter more particularly pointed out. The cylinder head 11 is provided on its inner side with a depending flange 17 which is so constructed and 45 arranged as to form with the upper section of the liner an annular super-compression space or chamber 18, as shown. Preferably passing through said flange 17 is a series of air 50 passages 19 which communicate at one of the ends with the upper or combustion chamber 10' of the cylinder, while the other ends are in communication with the super-compression space or chamber 18. 20 is a compressor ring fitted within the super-compression

55 chamber or space 18 provided with the usual packing rings 21 and adapted to abut or rest against the shoulder 22 on the upper end of the liner, when said ring 20 is in its lowest position. Said compressor ring 20 is also provided with a small port 23, which is adapted 60 to have its lower end in communication with the series of air passages 19 and its upper end with the upper section of the super-compression chamber or space 18, when said compressor ring 20 is in its lower position, for 65 purposes which will be presently described.

The inner portion of the central section of the cylinder head 11, is provided with a cylindrical recess 24 having screw threads 25 on a portion of its lower inner walls. 26 is a 70 distributor plate, preferably circular in form, provided on its cylindrical side with threads adapted to removably engage the threads 25 of the recess 24, and has its upper end abut against the inner side of the cylinder head 11, 75 and a portion is cut out therefrom so as to form an annular and shallow super-compressed air storage space, chamber or accumulator 27, within the cylinder head 11, and centrally arranged with regard to the 80 annular super-compression space 18. 28 is an opening centrally disposed at the inner section of the distributor plate 26, in which is properly arranged and disposed a fuel valve nozzle 29, which is carried and sustained by a fuel valve cage 29' and 30, fitted into an opening 31 in the cylinder head 11, as shown. 32 is a fuel chamber formed in the valve cage, which is adapted to receive the fuel by means of the passageway or duct 33, 90 connected with any source of liquid or other suitable fuel supply under pressure. 34 is a valve which controls the outlet of the fuel under pressure from the chamber 32 to the nozzle 29 for atomization in the combustion chamber 10', and may be actuated by any suitable valve mechanism, (not shown), common in this class of machines and forming no essential part of the present invention. 35 are a series of restricted ports or passageways 100 connecting the super-compressed air storage space or chamber 27 with the annular space 28 surrounding the end of the fuel valve nozzle 29, and are preferably and so arranged as to be oppositely and tangentially disposed 105 with respect to the openings 36 of the fuel valve nozzle 29, as shown for example in Figure 2, for the purpose of further atomizing

the atomized fuel issuing from the nozzle 29, and more particularly for causing a "turbulence" in the combustion chamber in order to effect a thorough intermingling of the air 5 within the cylinder and the injected fuel, and other functions to be hereinafter described. 37 are a series of air passages which connect the super-compressed air storage chamber or space 27 with the upper end of the super-com- 10 pression space or chamber 18, and each of said passageways 37 is provided with a check valve 38, as shown, for the purpose of preventing the return of the super-compressed air forced into the chamber 27 back into the 15 super-compression space or chamber 18.

The operation of the invention is as follows: Assuming the parts of the engine to be in the position as shown in the left half of Figure 1, it will be seen that the specially con- 20 structed displacement ring 16 on the upper end of the piston 13, is just about to engage and force the compressor ring 20 into the super-compression space or chamber 18. During the compression stroke of the piston 25 13, the air previously drawn in and confined in the cylinder is compressed and a portion of it is forced by said piston 13 through the series of passages 19 and port 23 into the super-compression space or chamber 18. On 30 further and last stages of the upward movement or compression stroke of the piston 13, the compressor ring 20 is forced into the space or chamber 18 so that said port 23 is no longer in communication with the series of ports 19, 35 and the entrapped air, which has been compressed by the compression stroke of the engine piston 13, is further or super-compressed by the action of said compressor ring 20 being displaced into said super-compression 40 space 18 when the displacement ring 16 on said piston 13 comes in contact with ring 20 and forces said ring into the position shown in the right half of Figure 1. The air super-compressed in chamber 18 is forced through 45 the check valves 38 into the super-compressed air storage or accumulator space 27, from whence it passes into the restricted air passages 35, not only to assist and complete the atomization of the finely divided fuel issuing 50 from the fuel nozzle 29, but also to effect a most important feature of the present invention by producing a turbulent action in the combustion chamber 10', which action insures a thorough intermingling of said fuel 55 and air, and complete and efficient burning of the fuel during the combustion phase of the cycle of operation.

From the foregoing description of the structural characteristics and relative ar- 60 rangement of the elements and operation of my invention, it will be readily seen that there is effected a super-compression of air within the cylinder walls by means of a se- 65 parate and independent compressor ring, fitted with packing rings to secure tightness,

The super-compression chamber is preferably a permanent part of the cylinder structure, and a removable displacement ring 16 pro- 70 tects the main piston 13 from possible injury and allows easy replacement of said ring 16 in case of its damage. With the use of an annular formed compressor piston or ring 20, the compression chamber 18 can be so located that its cross-sectional area will be a minimum for a given volume, the length of stroke re- 75 quired to attain a given compression is also reduced to a minimum, and the movement of the piston or ring 20 is slow and gentle, coinciding, as it does, with the retarded motion of the main piston 13 as it approaches the end 80 of its stroke, thereby reducing to a minimum the shock and wear on said ring or piston 20 and having a distinct and most important advantage over engines with a cam operated piston of considerable stroke, as previously 85 used in inventions of this class.

A further and most important feature of the disclosed arrangement is the provision and use of the accumulator or reservoir 27, to receive and store up the super-compressed air 90 delivered by each up-stroke of the ring or piston 20. In engines of the pure Diesel type where fuel is injected and combustion continues through a time period equivalent to a crank angle of 35 to 40 degrees for four-cycle 95 and about 20 degrees for two-cycle engines, where it is necessary to have the delivery of the super-compressed air continue throughout this period, such an adjustment can be readily secured by the disclosed construction 100 and arrangement of restricted air delivery ports 35 in said distributor plate 26. By properly proportioning the number and size of the restricted outlets of said ports 35, the time period required for the near equaliza- 105 tion of pressure in the accumulator or storage reservoir 27 and the combustion chamber 10' can be easily accomplished and made to coincide with or slightly overlap the period of fuel injection or combustion of the same in 110 the cylinder. It will also be manifest that by such an arrangement, throughout the ex- 115 pansion stroke, as the pressure within the cylinder falls, there will be a further expansion and flow of air from the accumulator or reservoir 27 through the ports 35, producing the same effect as proposed in the original Diesel engine patent, in which was provided a special chamber to expand a portion of the air of compression throughout the power 120 stroke, in order to maintain turbulence and secure equal heat distribution in the cylinder.

Another decidedly advantageous feature of the present invention is the construction 125 whereby the removable distributor plate 26 is designed to occupy an annular space or recess in the center of the cylinder head 11. The resultant central location of the accumulator or reservoir 27 formed by said plate 26 per- 130

mits the use of short delivery ports 35, and therefore insures correspondingly small pressure drop when direct delivery of the super-compressed air is contemplated, as in the present case.

A distinct innovation is also accomplished in the present construction and mode of operation by the use of super-compressed air for securing turbulence in the combustion chamber, 10 with special, not to say exclusive, reference to the oil burning solid injection type of engine. In using the term "solid injection", I refer to that variety of engine which does not utilize an air blast for injection and atomization of 15 the fuel, which class is known as the "air injection" type. The solid injection type of engine is a recently projected improvement upon the air injection type now in general use, and devised in order to do away with the trouble- 20 some air compressor attachment. However, the air blast of the air injection type has been particularly valuable in producing turbulence in the combustion chamber, and the absence of such turbulence in solid injection engines 25 is believed to be one of the main reasons for a lower combustion efficiency in this type. It is therefore believed that the use of super-compressed air for creating turbulence in the combustion space of a pure Diesel solid injection 30 type of engine will produce combustion efficiency equal to that of an air injection engine.

It should be noted that the preceding disclosure has dealt solely with the Diesel or 35 constant pressure combustion cycle, and the design as illustrated is arranged to meet the requirements of this cycle. The general idea of using super-compression to create turbulence is, however, equally applicable to the 40 constant volume combustion cycle. In this latter type of engine, the period of fuel injection is preferably completed before the end of the compression stroke, and this fact eliminates the necessity for the super-compressed 45 air storage chamber 27, the passages 37 and check valves 38, and permits the super-com- 50 pressed air piston 20 to be constructed as an integral part of the main piston 13. A suit- 55 ably modified design, adapted to the require- 60 ments of the constant volume combustion 65 cycle, is the basis of a separate and copending application, Serial No. 530,107, filed January 18, 1922.

While I have described and shown the preferred form of my invention, I do not limit myself to this specific form, as many changes and modifications will readily suggest themselves to any one skilled in the art, without departing from the spirit of my invention.

What I claim is:

1. An internal combustion engine comprising a cylinder having a combustion chamber, a piston within the cylinder, a fuel inlet for conveying fuel into the combustion chamber, 65 an annular air super-compression chamber in

communication with and surrounding said cylinder, an annular piston for super-compressing air in said air super-compression chamber, a super-compressed air storage chamber having an inlet in communication 70 with said air super-compression chamber, and an outlet in communication with said combustion chamber, constructed, arranged and adapted to produce turbulent action in said combustion chamber for the thorough intermingling of said fuel and air in said combustion chamber.

2. An internal combustion engine comprising a cylinder having a combustion chamber, a piston within the cylinder, a fuel nozzle for 80 conveying fuel into the combustion chamber, an annular air super-compression chamber communicating with and surrounding the compression end of the cylinder, an annular piston operated by the piston for super-compressing air in said air super-compression chamber, a super-compressed air storage chamber having an inlet in communication 85 with said air super-compression chamber and an outlet in communication with said combustion chamber, constructed, arranged and adapted to produce turbulent action in said combustion chamber for the thorough intermingling of said fuel and air in said combustion chamber.

3. An internal combustion engine comprising a cylinder having a combustion chamber, a piston within the cylinder, a fuel nozzle for conveying fuel into the combustion chamber, an annular-shaped air super-compression 100 chamber in communication with and surrounding the compression end of said cylinder, a separate and independent compressor ring in said air super-compression chamber, means on said piston for actuating said compressor ring for super-compressing air in said air super-compression chamber, a super-compressed air storage chamber having an inlet in communication with said air super-compression chamber and an outlet in communication 105 with said combustion chamber, constructed, arranged and adapted to produce turbulent action in said combustion chamber for the thorough intermingling of said fuel and air in said combustion chamber.

4. An internal combustion engine comprising a cylinder having a combustion chamber, a piston within the cylinder, a fuel nozzle for conveying fuel into the combustion chamber, an annular air super-compression 120 chamber in communication with and surrounding said cylinder, means for super-compressing air in said super-compression chamber, a super-compressed air storage chamber having an inlet in communication 125 with said air super-compression chamber and a series of outlets in communication with said combustion chamber so constructed and arranged in proximity to the fuel nozzle to complete the atomization of the admitted 130

fuel and also produce a turbulent action in said combustion chamber for the thorough intermingling of said fuel.

5. An internal combustion engine comprising a cylinder having a combustion chamber, a piston within the cylinder, a fuel nozzle for conveying fuel into the combustion chamber, an annular air super-compression chamber communicating with and surrounding the compression end of the cylinder, an independent piston operated by the piston in the cylinder for super-compressing air in said air super-compression chamber, a super-compressed air storage chamber having an inlet in communication with said air super-compression chamber and a plurality of outlets in communication with said combustion chamber, so constructed, adapted and arranged in proximity to the fuel nozzle as to complete the atomization of the admitted fuel and also produce a turbulent action in said combustion chamber for the thorough intermingling of said fuel.

6. An internal combustion engine comprising a cylinder having a combustion chamber, a piston within the cylinder, a fuel nozzle for conveying fuel into the combustion chamber, an annular-shaped air super-compression chamber communicating with and surrounding the compression end of the cylinder, a separate and independent compressor ring in said air super-compression chamber for super-compressing air in said super-compression chamber, an annular ring on said piston for actuating said compressor-ring, a super-compressed air storage chamber having an inlet in communication with said super-compression chamber and an outlet in communication with said combustion chamber, so constructed, adapted and arranged in proximity to the fuel nozzle as to complete the atomization of the admitted fuel and also produce a turbulent action in said combustion chamber for the thorough intermingling of said fuel and air.

7. An internal combustion engine comprising a cylinder having a combustion chamber, a piston within said cylinder, a fuel nozzle for conveying fuel into the combustion chamber, an annular air super-compression chamber within and surrounding the compression end of the cylinder and in communication with said combustion chamber and adapted to receive air compressed in the cylinder during the compression stroke of the piston, an annular super-compressed air storage chamber surrounding said fuel nozzle and having an inlet in communication with said air super-compression chamber and an outlet communicating with said combustion chamber in proximity to the fuel nozzle, an independent annular compressor ring within said air super-compression chamber for super-compressing the compressed air received from the cylinder, and a detachable ring on the

piston within the cylinder for actuating said compressor ring.

8. An internal combustion engine comprising a cylinder having a combustion chamber, a piston within the cylinder, a fuel valve nozzle for conveying finely divided fuel into the combustion chamber, means for controlling the fuel through said nozzle, an annular air super-compression chamber communicating with and surrounding the compression end of said cylinder and adapted to receive air compressed in the cylinder and forced therein during the compression stroke of the piston, an annular super-compressed air storage chamber within the cylinder and having an inlet in communication with said air super-compression chamber and a series of restricted outlets in proximity to said fuel valve nozzle and in communication with said combustion chamber for the purpose of assisting and completing the atomization of the finely divided fuel, and means within said air super-compression chamber operated by the piston for super-compressing the compressed air received from the cylinder.

9. An internal combustion engine comprising a cylinder having a combustion chamber, a cylinder head, a piston within said cylinder, a fuel nozzle for conveying fuel into the combustion chamber, an annular air super-compression chamber within the cylinder and in communication with said combustion chamber and adapted to receive air compressed in the cylinder during the compression stroke of the piston, an annular super-compressed air storage chamber in said head and having an inlet in communication with said air super-compression chamber and a series of outlets communicating with said combustion chamber in proximity to the fuel nozzle, an annular compressor piston within said air super-compression chamber for super-compressing the compressed air received from the cylinder, and means on the piston for actuating the compressor piston.

10. An internal combustion engine comprising a cylinder having a combustion chamber, a cylinder head, a piston within said cylinder, a fuel nozzle for conveying fuel into the combustion chamber, an annular air super-compression chamber within the cylinder and in communication with said combustion chamber and adapted to receive air compressed in the cylinder during the compression stroke of the piston, an annular super-compressed air storage chamber centrally disposed with respect to the super-compression chamber and having an inlet in communication with said air super-compression chamber and a series of outlets communicating with said combustion chamber in proximity to and surrounding the fuel nozzle, an independent and separate annular compressor piston within said air super-compression chamber for super-compressing the com-

pressed air received from the cylinder, and means on the piston within the cylinder for actuating the compressor piston.

11. An internal combustion engine comprising a cylinder having a combustion chamber, a head for the combustion chamber, an independent super-compressed air distributor plate removably attached to the inner side of said head, a fuel nozzle for conveying and atomizing fuel into the combustion chamber, an air super-compressing chamber, means for super-compressing air in said super-compressing chamber, a super-compressed air storage chamber in said distributor plate and having an inlet in communication with said air super-compressing chamber and an outlet independent of the fuel nozzle and in communication with said combustion chamber, said distributor plate, super-compressed air outlet being so constructed, arranged and adapted to produce turbulent action in said combustion chamber for the thorough intermingling of said atomized fuel and air in said combustion chamber.

12. An internal combustion engine comprising a cylinder having a combustion chamber, a head for the combustion chamber, an independent super-compressed air distributor plate removably attached to the inner side of said head, a fuel nozzle for conveying and atomizing fuel into the combustion chamber and surrounded by said distributor plate, an air super-compressing chamber, means for super-compressing air in said air super-compressing chamber, a super-compressed air storage chamber having an inlet in communication with said air super-compressing chamber and a series of restricted outlets independent of the fuel nozzle in communication with said combustion chamber, said distributor plate and super-compressed air outlet being so constructed, arranged and adapted to produce turbulent action in said combustion chamber for the thorough intermingling of said atomized fuel and air in said combustion chamber.

13. An internal combustion engine comprising a cylinder having a combustion chamber, a cylinder head, a head for the combustion chamber, an independent super-compressed air distributor plate removably attached and centrally disposed with respect to the inner side of said head, a fuel nozzle for conveying and atomizing fuel into the combustion chamber, an annular air super-compressing chamber within the cylinder head, means for super-compressing air in said air super-compressing chamber, a super-compressed air storage chamber adjacent to said distributor plate and having an outlet independent of the fuel nozzle and in communication with said combustion chamber, said distributor plate and super-compressed air outlet being so constructed, arranged and

adapted to produce turbulent action in said combustion chamber for the thorough intermingling of said atomized fuel and air in said combustion chamber.

14. An internal combustion engine of the oil-burning solid injection type comprising a cylinder having a combustion chamber, a cylinder head, a piston within the cylinder, a fuel nozzle for conveying and atomizing fuel into the combustion chamber, an annular super-compressed air storage chamber within the cylinder head and directly over the combustion chamber, and means independent of the fuel nozzle for conveying said super-compressed air into the combustion chamber for the purpose of producing turbulence in the cylinder.

15. An internal combustion engine of the oil-burning solid injection type comprising a cylinder having a combustion chamber, a cylinder head, a piston within the cylinder, a fuel supply chamber, a fuel nozzle for injecting and atomizing said fuel into the combustion chamber, an annular super-compressed air storage chamber within said cylinder head and directly over the combustion chamber, means for super-compressing air into said storage chamber, and means independent of the fuel nozzle for utilizing said super-compressed air to assist the injection, atomization and ignition of the fuel in the combustion chamber.

16. An internal combustion engine comprising a cylinder having a combustion chamber therein, a head for the combustion chamber, a fuel nozzle centrally within the head for conveying under pressure and atomizing fuel into the combustion chamber, an air super-compression chamber within the cylinder head, means for super-compressing air in said air super-compressing chamber, an air passage interposed between the said air super-compressing chamber and the combustion chamber, said passage being so constructed, arranged and adapted to receive air from the air super-compressing chamber and discharge it into the combustion chamber in proximity to, around and independent of the fuel nozzle and deliver the super-compressed air into the combustion chamber coincident with or overlapping the period of fuel injection, thereby producing a turbulent action in said combustion chamber for the thorough intermingling of said atomized fuel and air in said combustion chamber.

17. An internal combustion engine comprising a cylinder having a combustion chamber therein, a piston within the cylinder, a head for the combustion chamber, a fuel nozzle for injecting fuel into the combustion chamber, an annular air super-compression chamber coating with the engine piston for super-compressing air in said air super-compressing chamber, an air passage between the said annular air super-compression chamber

and the combustion chamber adapted to discharge air from the air super-compression chamber into the combustion chamber independently of the fuel nozzle and deliver the 5 super-compressed air into the combustion chamber coincidently with or overlapping the period of fuel injection, thereby producing a turbulent action in said combustion chamber for the thorough intermingling of said fuel 10 and air in said combustion chamber.

18. An internal combustion engine comprising a cylinder having a combustion chamber, a cylinder head, a piston within the cylinder, a fuel inlet for conveying fuel into the 15 combustion chamber, an annular air super-compression chamber formed by the cylinder and cylinder head, means for super-compressing air in said annular super-compression chamber, and means independent of said 20 fuel inlet for conveying said super-compressed air into the combustion chamber for producing turbulence therein.

19. An internal combustion engine of the oil-burning solid injection type comprising 25 a cylinder having a combustion chamber, a piston within the cylinder, a fuel nozzle delivering fuel to the combustion chamber, a cylinder head, a depending flange on the cylinder head, an annular air super-compression 30 chamber formed between said flange and the cylinder wall and communicating with said cylinder, an annular ring carried by the piston and arranged to enter the air super-compression chamber for the compression of air 35 therein, and means independent of said fuel nozzle for conveying the super-compressed air into the combustion chamber for producing 40 turbulence therein.

20. An internal combustion engine of the oil-burning solid injection type comprising 45 a cylinder having a combustion chamber, a piston within the cylinder, a fuel nozzle delivering fuel to the combustion chamber, a cylinder head, a depending flange on the cylinder head forming one wall of the combustion chamber, an annular super-compression chamber formed between said flange and the cylinder wall and communicating with the cylinder, annular means carried by the piston and arranged to enter the air super-compression chamber for the compression of air 50 therein, and means independent of said fuel nozzle for conveying the super-compressed air into the combustion chamber for producing 55 turbulence therein.

21. An internal combustion engine comprising a cylinder having a combustion chamber, a cylinder head, a piston within the cylinder having a head formed with a concave face, forming a concave inner wall of the combustion chamber, a fuel inlet for conveying fuel into the combustion chamber and arranged to deliver fuel into the piston concave, an annular air super-compression chamber formed by the cylinder and cylinder head, 60 means for super-compressing air in said annular super-compression chamber, and means independent of said fuel inlet for conveying said super-compressed air into the concave portion of the combustion chamber for producing 65 turbulence in said chamber. 70

22. An internal combustion engine comprising a cylinder having a combustion chamber, a piston within the cylinder, a fuel inlet for conveying fuel into the combustion chamber, an annular air super-compression chamber, in communication with and surrounding 75 said cylinder, an annular piston for super-compressing air in said air super-compression chamber, and a connection for the passage of air from said super-compression chamber to said combustion chamber, constructed, arranged and adapted to produce turbulent action in said combustion chamber for the thorough intermingling of said fuel and air 80 in said combustion chamber.

23. An internal combustion engine having a substantially cylindrical projection in the head of the cylinder thereof, said engine having a piston provided with a recess into which 85 said cylinder projection can enter, the top of the piston being of substantially annular shape and being adapted to enter the annular cylinder space between the wall of the cylinder and the annular projection thereof, 90 the parts being so dimensioned that when the said piston is moved inwardly upon its compression stroke the air in said annular cylinder space is compressed to a higher pressure than the air located in the recess of the 95 piston within the cylinder projection, said recess forming a part of a combustion chamber from which a powerful current of air is forced 100 from said annular cylinder space during a portion of the inner stroke of the piston, said combustion chamber having a fuel inlet communicating directly therewith. 105

In testimony whereof I affix my signature.

CHARLES G. BARRETT.
